Application July 5, 1934, Serial No. 733,819

5 Claims. (Cl. 229—8)

This invention relates to an ornamented box and an ornamental strip therefor. While not limited thereto, the box of the present invention is designed to serve as a container in which 5 cookies, candies and similar edibles are packed and sold.

In accordance with the present invention, a polygonally shaped box, e. g., a rectangular box, having plane-faced walls is made to present an 10 ornamental appearance by the assembly therewith of a strip of single-faced corrugated paper scored on a central longitudinal line extending perpendicularly to the corrugations of the corrugated ply and defining a pair of longitudinal laps. 15 The strip is engaged over substantially the entire upper edge of the box walls with the line of score substantially coincident with such edge and with one lap concealing the outer wall faces and the other lap concealing the inner wall faces, 20 the plane paper ply lying next to the wall faces and the corrugated ply being exposed to view. It is thus seen that the most conspicuous parts of the box, that is, its walls, are adorned both internally and externally by vertical corrugations, 25 which are especially attractive when the corrugated paper ply is translucent and/or tinted. In some cases, the plane paper ply of the ornamental strip may carry ornamentation imprinted on its face lying next to the corrugated translucent ply 30 so as to show through such latter ply.

With the foregoing and other features and objects in view, I shall now describe my invention in further detail with reference to the accompanying drawing, wherein,—

35 Figure 1 illustrates in perspective an ornamental strip embodying my invention.

Figure 2 is a similar view of a box with which the strip is to be assembled.

Figure 3 shows the completed or ornamented 40 box of the present invention.

As shown in Figure 1, the strip or band 10 constituting the ornamental element of the present invention consists of so-called single-faced corrugated paper and is made up of a plane or flat 45 paper ply 11 to one face of which is adhesively secured a corrugated paper ply 12. As already indicated, the corrugated paper ply is preferably of a translucent variety such as typified by so-called glassine and parchment papers. The plane 50 paper ply may be of a variety similar to the corrugated one, although it may well consist of bond or other suitable paper. The strip is characterized in that the corrugations run transversely of its longitudinal median line so that it flexes easily 55 along the lines of the corrugations but is com-

paratively stiff or inflexible on lines running perpendicularly to the corrugations. The strip is scored, as illustrated in Figure 1, along a central longitudinal line $x-x$ which makes possible easy flexing of the strip along such line without injury to or distortion of the corrugations.

The strip is designed for assembly with a rectangular box having plane-faced walls, such as shown in Figure 2. The box may, if desired, be made from inexpensive paperboard presenting a poor appearance, for instance, paperboard having the grayish cast characteristic of manufacture largely from waste papers or groundwood pulp. The strip is engaged over the upper edge of the box with its line of score $x-x$ substantially coincident with such upper edge, the line of score defining a pair of longitudinal laps 14 and 15. The length of the strip is such that it runs the full length of the entire upper edge; and its width is such to ensure a complete concealment of both the inner and outer faces of the box walls by its laps. The laps are bent down so that the plane paper ply lies to the wall faces, whereas the corrugated ply is exposed to view. When the laps are thus bent down against the wall faces of the box, as appears in Figure 3, they tend to remain bent by virtue of the tendency for the strip to remain permanently bent when bending is done across the corrugations and of the frictional engagement between the corrugations on the inside corners of the box. In order to prevent crowding or distortion of the corrugations such as is apt to result on the inside corners of the box, it is preferable, as shown in Figure 1, to slit one of the laps 14 along lines $y-y$ corresponding to each of the three corners of the box, the lines of slit thus extending perpendicularly from a side edge of the strip to its central longitudinal line $x-x$. The end edges 16 of the strip meet at the fourth corner of the box, as shown in Figure 3.

When cookies, candies, or other articles are packed in the box, they tend to keep the inner lap 14 of the strip against the inner wall faces of the box. The box of the present invention and its contents are preferably wrapped in transparent sheet material, for instance, the thin transparent film or sheet of regenerated cellulose known as "Cellophane", which permits the vendor to view the ornamented box and its contents and which holds the outer lap 15 against the outer wall faces of the box. In addition to the ornamental value of the strip, it serves to enhance the rigidity of all of the walls of the box, the corrugations of the strip extending vertically both on the inside and outside of the walls so as to furnish resistance.

against bending, bulging, or tearing of the walls. It is thus seen that, in accordance with my invention, the box is improved both in appearance and structurally in a simple and economical way, as 5 my invention calls for the use of merely a single strip of decorative material which can be assembled in operative relationship with the box without need for adhesives or other fastening means.

10 The principles of the present invention extend to other than rectangular boxes, for instance, triangular, pentagonal or other polygonally shaped boxes, in each of which case, the ornamental strip should preferably be provided with a number of 15 slits $y-y$ in its inner lap comporting with the number of corners present in the box.

I claim:

1. The combination with a polygonally shaped box having plane-faced walls, of a strip of single-faced corrugated paper scored on a central longitudinal line extending perpendicularly to the corrugations of the corrugated ply and defining a pair of longitudinal laps, said strip being engaged over substantially the entire upper edge of 25 the box walls with the line of score substantially coincident with said edge and with one lap concealing the outer wall faces and the other lap concealing the inner wall faces, the plane paper 30 ply lying next to the wall faces and the corrugated ply being exposed to view.

2. The combination with a polygonally shaped box having plane-faced walls, of a strip of single-faced corrugated paper scored on a central longitudinal line extending perpendicularly to the 35 corrugations of the corrugated ply and defining a pair of longitudinal laps, said strip being engaged over substantially the entire upper edge of the box walls with the line of score substantially coincident with said edge and with one lap 40 concealing the outer wall faces and the other lap concealing the inner wall faces, the plane paper 45 ply lying next to the wall faces and the corrugated ply being exposed to view, said lap concealing the inner face of said walls being slit at corners of the box by lines of slit extending perpendicularly from the side edge of the strip to said central longitudinal line.

3. The combination with a rectangular box having plane-faced walls, of a strip of single-faced corrugated paper scored on a central longitudinal line extending perpendicularly to the 50

corrugations of the corrugated ply and defining a pair of longitudinal laps, said strip being engaged over substantially the entire upper edge of the box walls with the line of score substantially coincident with said edge and with one lap concealing the outer wall faces and the other lap concealing the inner wall faces, the plane paper 80 ply lying next to the wall faces and the corrugated ply being exposed to view, said lap concealing the inner face of said walls being slit at three corners of the box by lines of slit extending perpendicularly from the side edge of the strip to said central longitudinal line and the end edges of said strip meeting at the fourth corner.

4. An ornamental strip for a polygonally shaped box having plane-faced walls comprising a strip of single-faced corrugated paper scored on a central longitudinal line extending perpendicularly to the corrugations of the corrugated ply and defining a pair of longitudinal laps, said strip being adapted for engagement over the entire upper edge of the box walls with the lines of score substantially coincident with said edge and with one lap concealing the outer 90 wall faces and the other lap concealing the inner wall faces, the plane paper ply being adapted to lie next to the wall faces, one of said laps being slit along lines corresponding to corners of the box and extending perpendicularly from a side edge of the strip to said central longitudinal line.

5. An ornamental strip for a polygonally shaped box having plane-faced walls comprising a strip of single-faced corrugated paper 100 scored on a central longitudinal line extending perpendicularly to the corrugations of the corrugated ply and defining a pair of longitudinal laps, said strip being adapted for engagement over the entire upper edge of the box walls with the lines of score substantially coincident with said edge and with one lap concealing the outer 110 wall faces and the other lap concealing the inner wall faces, the plane paper ply being adapted to lie next to the wall faces, one of said laps 120 being slit along lines corresponding to corners of the box and extending perpendicularly from a side edge of the strip to said central longitudinal line, said corrugated ply consisting of translucent paper.
